JOSEPH TOMLINSON, OF CHICAGO, ILLINOIS, ASSIGNOR TO COX MULTI-MAILER COMPANY, OF AUGUSTA, MAINE, A CORPORATION OF MAINE.

FEEDING DEVICE.

1,159,623.

Specification of Letters Patent.

Patented Nov. 9, 1915.

Application filed January 13, 1913. Serial No. 741,653.

To all whom it may concern:

Be it known that I, JOSEPH TOMLINSON, a citizen of the United States, residing at Chicago, in the county of Cook and State of Illinois, have invented certain new and useful Improvements in Feeding Devices, of which the following is a specification.

This invention relates to a device for feeding books, pamphlets and the like, from a stack thereof to a printing press or folding machine, and the principal object of the invention is to provide a simple, durable and inexpensive device of the class described, which may be readily and easily adjusted to accommodate books or pamphlets of different thicknesses, so that only a single book or pamphlet or a predetermined number of them may be moved from beneath a pile or stack of the same in position to be gripped and fed to a printing or folding machine.

A further object of the invention is to provide means for adjusting the number of books or pamphlets which may be fed at one time.

For the attainment of these ends and the accomplishment of other new and useful objects, as will appear, the invention consists in the features of novelty, in the construction, combination and arrangement of the several parts, generally shown in the accompanying drawings and described in the specification, but more particularly pointed out in the appended claims.

In the drawings Figure 1 is a top plan view of a device constructed in accordance with the principles of my invention. Fig. 2 is a sectional view of the same taken on the line 2—2 of Fig. 1.

In feeding magazines, pamphlets and the like, to a printing or folding machine, it is customary to employ a hopper in which the books or magazines are placed and from which they are fed, one or more at a time, to the printing or wrapping machine. It is customary to pile the books or pamphlets in a stack upon a feeding plate which reciprocates, moving one or more of the books or pamphlets from the bottom of the stack. If

the books or pamphlets are piled in a vertical pile, the weight of the stack limits the height thereof, so that only a certain number of books may be disposed in the stack to enable the feeding mechanism to work properly. In other words, when the stack

is too high, the pressure on the lowermost book is so great that it is very difficult to feed it from under the stack. The present invention overcomes this difficulty by inclining the stack of books or pamphlets at a certain angle, thereby relieving the pressure upon the lowermost books or pamphlets, so that they may be easily and readily fed from the bottom of the stack.

Referring now more particularly to the drawing, the numeral 5 designates generally a support or standard of any desired or suitable form and construction, which is formed with projecting sides 6 spaced apart and provided on the inside with inclined grooves 7. Movable in the grooves 7 is a slide 8 provided with a shoulder 9 upon its upper portion of any desired or suitable height and with one or more depending lugs or projections 10 intermediate of the ends of the slide. Suitably mounted upon the support 5 and secured thereto is a hopper 11 disposed over the slide 8 and with a transverse portion 12 extending substantially at right angles to the slide 8 and the grooves 7. This transverse portion 12 terminates at a distance above the slide and is preferably provided with one or more slots 13. A movable plate 14 is disposed against the transverse portion 12 within the hopper and extends downwardly toward the slide. The plate 14 is adjustable with respect to the slide, so that one or more pamphlets of any thickness may be fed from a stack 15 disposed in the hopper, and any desired or suitable means may be employed for adjusting the position of the plate 14 with respect to the slide. Preferably, however, the plate is provided with a thumb screw 16 threaded into the plate and having a washer 17 disposed thereon, the thumb screw being inserted through one of the slots 13 in the transverse portion of the hopper. In order to move the slide in the grooves 7 and to grip the book or pamphlet as it is moved from beneath the stack thereof, any desired or suitable means may be employed, such, for example, as that shown in the drawings.

A plurality of shafts 18, 19, 20 and 21 are rotatably mounted in the support 5, and extending transversely of the slide 8 and providing a support for the gears 22, 23, 24 and 25, which mesh with each other and are driven by any desired or suitable engaging means, such, for example, as a gear 26. One

of the shafts, as 18, is also provided with a plate 27 having a crank pin 28 projecting therefrom, and a link 29 forms connection between the crank pin and the projection 10, which depends from the plate 8 so that the rotation of the shaft 18 together with the plate 27 will cause the crank 29 and the slide 8 to be reciprocated. One of the other shafts, as 22, is provided with a roller 30, the upper face of which is preferably flush with the upper face of the slide 8 and is adapted to engage the lower face of a book or pamphlet when moved into position by the said slot. A second roller 31 is rotatable upon a shaft 32 and is disposed in a position to engage the upper face of the book or pamphlet as it is moved from beneath the stack of the same in the hopper.

In operation it is necessary only to adjust the plate 14 to present an opening of the desired width at the bottom thereof between the lower edge of the plate and the upper face of the slide 8, so that when the slide is reciprocated, the books or pamphlets will be fed from the bottom of the stack in accordance with the position of the plate 14, so that any desired number of pamphlets may be fed at the same time. In order to produce the required result, it is necessary that the stack of books or pamphlets be inclined so that the entire weight thereof will not rest directly upon the slide 8, and for this purpose the slide is inclined in the direction of feeding and the plate 14 is correspondingly inclined and is preferably disposed at right angles to the plane of the slide. It is found upon experimentation that the best results are attained when the slide and the plate are disposed at an angle of substantially thirty degrees from the horizontal and vertical, respectively. With the plate of the hopper disposed at this angle, the books to be fed therefrom may be piled in the hopper to any desired height and after a certain height is reached the pressure on the lowermost book will not be appreciably increased by the addition of more books, so that it is easily possible to keep a stack of books in the hopper at all times, so that they may be fed regularly by the feeding slide. This inclination is also of material assistance in properly positioning the books or pamphlets, in the hopper, for they will take the proper position by the action of gravity alone, so that they will be properly presented to the shoulders of the slide and may be easily and regularly fed thereby until they are engaged by the gripping rollers 30 and 31. Although an angle of substantially thirty degrees is found best for the inclination of the slide and plate, it is obvious that a slight variation from this angle will not produce materially different results and the angle may depend somewhat upon the nature of the articles to be fed

from the feeding device and the height of the stack which may be maintained in the hopper.

What I claim is:

1. In a device for feeding books and the like to a printing or folding machine, the combination with a support having parallel members spaced apart with the grooves on the inside thereof inclined to the horizontal, a slide provided with an upwardly extending shoulder and a depending projection and slidable in said grooves, a hopper disposed above the slide and secured to said support comprising side pieces and an inclined transversely extending portion terminating at a distance above the slide and having slots therethrough, a plate disposed within the hopper against the said portion, and thumb-screws inserted through said slots and threaded into the plate to position the plate with respect to the slide, shafts rotatably mounted in said support, interengaging gears mounted on said shafts, a crank plate mounted on one of said shafts, a crank to connect the depending projection of said slide to the plate to reciprocate the slide when the plate is rotated, and rollers mounted upon others of said shafts and disposed to engage, grip, and withdraw the books from the hopper when fed therefrom by the slide, one of said gears forming a driving connection for the other gears and the rotatable shafts.

2. In a feeding device of the class described, the combination of an inclined reciprocatory shouldered slide upon which the articles to be supported rest, the slide constituting the sole support for the lowermost articles, the shoulder of which engages the rear of the lowermost article to feed it forwardly, and a hopper having an inclined side upon which articles to be fed are partially supported to take some of the weight from the slide.

3. In a feeding device of the class described, the combination with a reciprocatory slide inclined in the direction of feeding upon which the articles to be fed are partially supported, the slide constituting the sole support for the lowermost articles, having a shoulder which engages the rear of the lowermost article to feed it forwardly, and a hopper with the side inclined from the perpendicular and at right angles to the slide upon which articles to be fed are also partially supported to insure that the pressure of the lowermost article upon the slide is substantially constant regardless of the height of the articles in the hopper.

4. In a feeding device of the class described, a reciprocatory slide inclined in the direction of feeding upon which the articles to be fed are partially supported, the slide constituting the sole support for the lowermost articles, having a shoulder which en-

gages the rear of the lowermost article to feed it forwardly, a hopper above the slide with an inclined side upon which a stack of articles to be fed is also partially supported for maintaining uniform pressure on the lowermost article, and a plate adjustable toward and from the slide to limit the number of articles which pass from the bottom of the stack at each feeding movement 10 of the plate.

5. In a feeding device of the class described, the combination of a shouldered reciprocating slide and a hopper, both inclined from the horizontal and approximately at right angles to each other to form 15 a mutual support for articles contained in the hopper and resting on the slide, so that

only a part of the weight of the articles in the hopper will fall on the slide, thereby limiting the pressure of the articles upon 20 the slide, the slide constituting the sole support for the lowermost articles, the shoulder of the slide being adapted to engage the rear of the lowermost article below the top surface thereof to feed it forwardly when 25 the slide is reciprocated.

In testimony whereof I have signed my name to this specification, in the presence of two subscribing witnesses, on this 9th day of January A. D. 1913.

JOSEPH TOMLINSON.
